(57) **CLAIM**

The ornamental design for a computer tower holder, as shown and described.

DESCRIPTION

FIG. 1 is a first perspective view of an embodiment of a computer tower holder embodying the new design;

FIG. 2 is a second perspective view thereof;

FIG. 3 is a third perspective view thereof;

FIG. 4 is a front view thereof;

FIG. 5 is a back view thereof;

FIG. 6 is a left side view thereof;

FIG. 7 is a right side view thereof;

FIG. 8 is a top view thereof; and,

FIG. 9 is a bottom view thereof.

Broken lines are used in the figures to illustrate portions of the computer tower holder that form no part of the claimed design.
